UNITED STATES PATENT OFFICE.

THOMAS L. PARKER, OF CHICAGO, ILLINOIS, ASSIGNOR TO THE STANDARD ELECTRIC MANUFACTURING CO., OF CHICAGO, ILLINOIS, A CORPORATION OF ILLINOIS.

SNAP-SWITCH.

1,389,213.

Specification of Letters Patent. Patented Aug. 30, 1921.

Application filed March 2, 1918. Serial No. 219,949.

To all whom it may concern:

Be it known that I, THOMAS L. PARKER, a citizen of the United States, residing at Chicago, in the county of Cook and State 5 of Illinois, have invented certain new and useful Improvements in Snap-Switches, of which the following is a description.

My invention belongs to that general class of devices known as snap switches, particularly the type known as push button snap switches. The invention has among its objects the production of a device of the kind described that is simple, compact, convenient, durable, safe, efficient and satisfactory for use wherever found applicable. It has particularly as an object the production of a switch of the kind described that will operate easily, smoothly and substantially noiselessly and which will have 10 a quick movement so that there will be no arcing and burning of the brushes or contacts. It has as an additional object the production of a device which may be easily and economically constructed and assembled. 15 Many other objects and advantages of the construction herein shown and described will be obvious to those skilled in the art from the disclosure herein given.

To this end my invention consists in the 20 novel construction, arrangement and combination of parts herein shown and described and more particularly pointed out in the claims.

In the drawings, wherein like reference 25 characters indicate like or corresponding parts,

Figure 1 is a front elevation of one type of the switch, the usual cover plate removed;

Fig. 2 is a sectional view taken substantially on line 2—2 of Fig. 1;

Fig. 3 is a sectional view taken substantially on line 3—3 of Fig. 1;

Fig. 4 is a sectional view taken substantially on line 4—4 of Fig. 1;

Fig. 5 is a sectional view taken substantially on line 5—5 of Fig. 1;

Fig. 6 is a sectional view taken substantially on line 6—6 of Fig. 2;

Fig. 7 is a perspective view of the brush 50 carrying member;

Fig. 8 is a perspective view of the rocker arm;

Fig. 9 is a perspective view partly illustrating an assembly of the parts shown in 55 Figs. 7 and 8;

Fig. 10 is a sectional view through a portion of the brush carrying member and brushes;

Fig. 11 is a sectional view taken substantially on line 11—11 of Fig. 12 through the 60 rocker arm and button stem;

Fig. 12 is a sectional view taken substantially on line 12—12 of Fig. 11;

Fig. 13 is a view similar to Fig. 1 of a 65 double pole switch;

Fig. 14 is a view similar to Fig. 9 of the mechanism for controlling the brushes of the same;

Fig. 15 is a sectional view similar to Fig. 2 of a three way switch showing the brushes 70 as seen from one side;

Fig. 16 is a similar sectional view taken through the other side, showing the brushes as seen from the other side; and

Fig. 17 is a side elevation of the brush 75 carrier and brushes of the same.

Referring to the drawings, 1 represents a plate of suitable size, shape and material, and 2 a base or receptacle of suitable size, shape and material, porcelain or like 80 insulating material being preferably employed. The parts 1 and 2 may be secured together by the screws 3—3 or the equivalent for the purpose. I have shown a single switch having the two operating buttons 4 85 and 5, the same projecting into the recess or chamber of the receptacle 2 and being connected with the switch mechanism as hereafter described.

Arranged within the receptacle are the 90 bracket or base arms 6—6 carrying the brush controlling and operating mechanism, which arms may be secured in any place in any suitable manner. As shown, the same are provided with the lugs 7—7, etc., which ex-

tend through the plate 1 and upset at the end so that the arms are substantially riveted onto the plate 1, and to all intents and purposes are the same as if formed integral 95 with the plate 1. These arms are preferably formed with the free ends rounded as at 8, and with stops 9 at each side, and they carry studs 10, or the equivalent, on the outside face of each and studs 11, or the equivalent, on the inside faces. In the 100

preferred construction these studs are formed by punching a portion of the body of the material outwardly or inwardly as the case may be, as illustrated in Figs. 4 and 10. Obviously the two bracket arms 110

6 may be stamped out by suitable dies or in an equivalent manner.

Referring to Fig. 8, the rocker arm or button connecting member is shown, which 5 consists of a part 14 turned or bent down at each side, so that it is substantially U-shape to provide arms 15 and 16, which are slotted or similarly formed at 17 to form bearings arranged to coöperate with 10 the lugs 11 as will be hereafter described. The arm at one side or one leg of the U-shaped part, as shown arm 16, is extended as at 18—18 and provided with an extending part 19 adjacent each free end, the 15 outer end of 19 being formed as at 20, or in an equivalent manner. Each button is provided with a part 21 of suitable size, shape and material, the same being preferably bent or offset as most clearly shown 20 in Fig. 11, and provided with an opening 22 having an open side between the ends 23. Part 21 is connected to the part 18 by positioning the extending part 19 into the recess 22, the ends 23 being preferably close 25 together as most clearly shown in Fig. 5. I have shown the hole 22 substantially round with a portion cut away at one side so as to form a suitable bearing, it being possible to slip the parts together or assemble them after they are completely 30 formed. However, after assembling and turning the parts in their normal positions, they are locked against accidental disengagement. Parts 21 and the connecting 35 member shown in Fig. 8 may be suitably formed by dies or the equivalent. It will be noted that a loop 24 is formed or provided on the part 14, the purpose of which will be explained hereafter.

40 The brush carrying member is also preferably U-shape, and is shown in perspective in Fig. 7, in which 26 is a part turned down as at 27—28 at each side to form arms or legs, the same being preferably slotted as 45 at 29 to form bearings arranged to engage with the studs 10 in the outer face of each member 6 (see Fig. 4). At one or both sides (Figs. 1 to 10, as shown one side 28), the same is formed with the extending parts 50 30, which at their ends are formed with posts or pins 31. The posts or pins 31 carry the brush members 32, the ends 33 of which are preferably spaced and formed so as to embrace the contact members 47. The 55 brush members are shown secured on the pins 31 between plates 34 and 45, preferably of metal, and plates 36 and 37 of insulating material such as rubber, mica, fiber or the like. It will be noted by referring to Fig. 10 that the insulating material is so arranged as to insulate the brushes and the pins 31. I prefer to make a round projection extending through the brushes and a square or rectangular hole through 65 65 which the pins 31 pass. The several parts

just described are secured together by upsetting or riveting down the ends of pins 31 as shown. The cross part 26, as most clearly shown in Figs. 7 and 9 as well as Fig. 5, is formed or provided with a loop 39. A spring 40 engaging with the loop 24 and loop 39 connects the parts 14 and 26 together. 70

The body or porcelain receptacle 2 is preferably recessed or chambered as at 42 and carries the contact members 47 previously referred to. In the construction shown, receptacle 2 is provided with shoulders or faces 43, upon which are mounted the plates 44 secured in place by screws 45 or the equivalents extending through the porcelain. Each contact member or plate 44 is turned down as at 46 into the recess (see Figs. 2 and 4) and the lower or inner end is turned outwardly from the porcelain 80 as at 47 to provide the contacts arranged to coöperate with the brush ends. Obviously the brush parts 32 may be in the form of a single blade and the contacts 47 be similar to the brush parts shown and embrace 85 the blade. In the preferred construction these contacts and associated parts are so arranged and proportioned that the brush may be straight, and when in operative position extends across the recess and engages 90 the contacts on opposite sides thereof. When the button 5 is depressed the brush end adjacent that button will move outwardly and the opposite end inwardly, the parts being so proportioned and arranged 100 that the brushes are separated equally from their respective contacts. This is very desirable as it enables the device to be made very compact and permits better standardizing of the various parts. The conducting 105 wires may be secured to or connected with the plates 44 by means of the screws 48 or their equivalents, 49 being an upturned lug on each plate arranged to retain the conducting wire under the screw head. 110

As most clearly shown in Fig. 1 as well as Fig. 3, the plate 1 is provided with the extended ends 51 and with the holes 52 and 53 as well as 54. Holes 52 may be threaded to engage suitable screws for securing the 115 cover plate P, shown in dotted lines in Fig. 2 in place, while the holes 53 and 54 are arranged to receive screws or bolts for securing the switch in its receptacle or to where desired, the particular holes 53 or 54 used 120 depending upon the receptacle or box, it being the usual practice to arrange the switch shown in a metal or other box. I have shown the porcelain cut away as at 55, 56 and 57, the purpose of the cut-out being 125 obvious. While I have shown but a single switch and base, it will be obvious that the same may be assembled in gangs, each usually having its individual porcelain receptacle, or in some cases one porcelain recep- 130

tacle may be provided arranged to receive any desired number of switch mechanisms.

In assembling the switch parts the spring 40 is attached to the part 14 of the rocker

5 arm and the same set in position on the brackets 6-6 with the pins or lugs 11 in the bearings 17. It is then moved to one side and one button is placed and then turned over and the other button positioned.

10 The brush carrier is now set in position and the spring 40 attached thereto as shown. The mechanism, contacts, etc. may then be secured to the porcelain and the switch is complete. It will be noted that removing

15 plate 1 removes the assembled mechanism described, and replacing the plate replaces the same.

The operation of the switch may be best described by referring to Figs. 3, 5 and 9.

20 As the parts are shown, contacts 47 are connected by the brushes and the circuit closed through the switch. If now button 5 is depressed this will rock the rocker arm about the studs 11, carrying the end of spring 40

25 past the lugs 10 and 11, and the spring drawing on the connecting part 26 will snap the brush carrier to the opposite side, thereby throwing the brushes out of contact with the contact members and breaking the circuit.

30 The spring, however, will maintain the brush in this position until the other button is again pushed, thereby moving the spring past the studs again until the same passes them, and then throws the brush carrier to

35 the opposite side about its pivotal supporters or studs 10, thereby again closing the circuit.

It will be noted that when the part 26 is thrown from one side to the other it bears

40 against the parts 21 which serve as stops, so that all the parts are held securely. Owing to the improved construction, not only may the parts be very cheaply manufactured in so far as labor is concerned, but also as to

45 the quantity of material used, and in assembling the completely constructed parts may be slipped together without additional riveting, bending, soldering or like operations.

50 Referring to Fig. 13 in which the double pole switch is shown, it may be mentioned that this switch is substantially like the single pole switch previously described except that the receptacle 2' is made some-

55 what wider and the brush carrier is arranged to carry brushes at each side. In this case, in place of the brush carrier shown in Fig. 7, I provide a brush carrier (see Fig. 14), consisting of the part 59, correspond-

60 ing with 26, having turned down portions 60 corresponding to 28, each turned down portion being provided with the brush carrying flanges 61 corresponding with 30, terminating in lugs or pins upon which the brushes

65 32 are mounted. The receptacle is also pro-

vided with an additional set of contacts for the extra brushes. In other respects the construction is substantially similar to that shown in Figs. 1 to 12.

Figs. 15, 16 and 17 illustrate the three 70

way switch which is provided with two sets of brushes. In this case the receptacle and contacts are similar to that shown in Fig. 13, and the brush carrier 64-65 is similar

75 to that shown in Fig. 14 except that the parts corresponding to 60 at each side are so arranged that the brushes are not in alignment but are at an angle to each other, so

that pushing one button closes the circuit between the two contacts and its respective 80 brush and breaks the circuit through the other brush. Pushing the other button

breaks the circuit at the first mentioned brush and closes the same through the other brush. With this type of switch the contacts may be connected up as desired so as

85 to afford different wiring combinations. With the exception of the difference mentioned the switch corresponds substantially with that shown in Figs. 1 to 14. It will be

90 particularly noted in this connection that with the three types of switches the only changes are in the brush carriers, the difference in the receptacles and the additional contacts. As a matter of fact any of the

95 switch mechanisms may be used in the type of receptacle 2' shown in Fig. 13. The receptacle shown in Fig. 1, however, is not as wide and is not constructed with as large a

100 recess as it is found advantageous where possible to have the receptacle substantially small.

Having thus described my invention, it is obvious that various immaterial modifications may be made in the same without departing from the spirit of my invention, hence I do not wish to be understood as limiting myself to the exact form, construction, arrangement and combination of parts herein shown and described or uses mentioned.

What I claim as new and desire to secure by Letters Patent is:—

1. In a snap switch of the kind described and in combination, a plate, a pair of spaced bracket arms carried by said plate, said bracket arms each having bearings projecting from the inner and outer faces thereof, a brush carrier having open bearings and detachably mounted on the bearings at the 115 outer faces of said bracket arms, a rocker arm having open bearings and detachably mounted on the bearings at the inner face of said brackets, a spring connecting said brush carrier and said rocker arm, and co-operating buttons for said rocker arm.

2. In a switch, a brush, actuating mechanism therefor including a rocker arm consisting of a U-shaped part provided with open bearings at the free end of each of the 130

- sides, one side having an extending arm at each edge, said arms each provided with a T-shaped offset near the free end extending toward the other side of the U, and a button 5 for each arm provided with a stem, said stems each formed with an open bearing arranged to engage the adjacent offset.
3. In a switch, a brush and brush carrier, actuating mechanism therefor including a 10 rocker arm consisting of a U-shaped part provided with open bearings at the free end of each of the sides, one side having an extending arm at each edge provided with an inwardly extending T-shaped offset near the 15 free end and extending toward the other side of the U, a button for each arm, each button provided with a stem formed to engage said offsets between the arm and head of the T, said stem cut away to permit the 20 assembly of the stem on said arm.
4. In a snap switch of the kind described and in combination, a recessed receptacle, a plate arranged over the recess in said receptacle and provided with a pair of bracket 25 arms extending into said recess, a brush carrier part consisting of a single piece of material bent at the ends to form a U-shaped piece and provided with open bearings at the free ends thereof, said part journaled 30 on the outer faces of said bracket arms and movable past the free ends thereof, one side of said part provided with a flange, a contact member carried by said flange, a rocker arm consisting of a single piece of 35 material bent at the ends to provide a substantially U-shaped part and formed with bearings at the free ends, said part being journaled on said bracket arms at the inner sides thereof, said part having an extend- 40 ing arm at both sides of one of the bent over ends, a plurality of buttons each having a stem, and integrally formed means on each arm adjacent the end thereof for securing said stems.
- 45 5. In a snap switch of the kind described and in combination, a receptacle provided with a recess therein and having a contact member at each end of said recess, a plate extending over said recess and secured on 50 said receptacle, a pair of spaced bracket arms carried by said plate and projecting into said recess in said receptacle, a brush carrier consisting of a U-shaped part provided with flanges on one of the sides of the 55 U pivotally secured on the outer faces of said bracket arms, a straight brush carried by said flanges, said brush arranged to coöperate with and bridge said contact members in said recess, actuating means for said carrier 60 comprising a U-shaped rocker arm part pivotally secured on the inner faces of said bracket arms and connected with said carrier, one side of said U-shaped rocker arm part having an extending arm at each edge, 65 a button for each of said arms, each button

having a stem, and integrally formed means at the end of each arm for operatively securing the stem to its respective arm.

6. In a snap switch of the kind described and in combination, a receptacle formed 70 with a recess therein, a plate extending over said recess, a pair of spaced bracket arms carried by said plate and projecting into the recess, said bracket arms having integrally formed bearings projecting from the 75 inner and outer faces thereof and each formed with a curved free end with a stop at each side thereof, a brush carrier member detachably mounted on the bearings of said outer faces of said arms and slidable on said 80 curved faces, a rocker arm member detachably mounted on the bearings at the inner side of said brackets, a spring connecting the two members, operating buttons for said rocker arm, and contacts for 85 said brushes arranged in said recess adjacent the ends of the brushes.

7. In a switch of the kind described and in combination, a receptacle, a plate secured thereto and arranged for attachment to a 90 coöperating part, bracket arms provided with integrally formed studs and carried by said plate and extending into said receptacle, a contact carrier having open bearings and detachably mounted on the studs on said 95 bracket arms, contact members carried by said carrier at each side thereof, a rocker arm having open bearings and detachably mounted on the studs on said bracket arms and resiliently connected with said brush 100 carrier, and a plurality of coöperating contact members for each of said first mentioned contact members carried by said receptacle.

8. In a snap switch of the kind described and in combination, a recessed receptacle, a plate arranged over the recess in said receptacle and provided with a pair of bracket arms extending into said recess, a brush carrier consisting of a single piece of material bent at the ends to form a U-shaped part and provided with open bearings at the free ends thereof, said part journaled on the outer faces of said bracket arms, said part provided with flanges at each side, contact 110 members carried on each side of said carrier by said flanges, a rocker arm consisting of a single piece of material bent at the end to provide a substantially U-shaped part and formed with bearings at the free ends, 115 said part being journaled on said bracket arms at the inner sides thereof, said part having an extended arm at both sides of one of the bent over ends, connecting means between said carrier and rocker arm, a plurality of buttons, one connected to one extending arm and the other to the other arm, and a plurality of contact members for each of said first mentioned contact members arranged in the recess in said receptacle, and 120 125 130

arranged for connection with suitable conductors.

9. In a snap switch of the kind described and in combination, a recessed receptacle, a 5 plate arranged over the recess in said receptacle and provided with a pair of bracket arms extending into said recess, a brush carrier consisting of a single piece of material bent at the ends to form a U-shaped 10 part and provided with open bearings at the free ends thereof, said part journaled on the outer faces of said bracket arms and movable past the free ends thereof, said part provided with flanges at each side, straight 15 contact members carried on each side of said carrier by said flanges, one member being turned at an angle relative to the other, a rocker arm consisting of a single piece of material bent at the end to provide a substantially U-shaped part and formed with 20

bearings at the free ends, said part being journaled on said bracket arms at the inner sides thereof, said part having an extended arm at both sides of one of the bent over ends, resilient connecting means between 25 said carrier and rocker arm, a plurality of buttons, one connected to one extending arm and the other to the other arm, and a plurality of contact members for each of said first mentioned contact members arranged in the recess in said receptacle, and 30 arranged for connection with suitable conductors.

In testimony whereof, I have hereunto signed my name in the presence of two sub- 35 scribing witnesses.

THOMAS L. PARKER.
